United States Patent Office.

GEORGE C. WILDER, OF LAWRENCE, KANSAS.

Letters Patent No. 84,039, dated November 10, 1868.

IMPROVEMENT IN PUNCHES.

The Schedule referred to in these Letters Patent and making part of the same.

To all whom it may concern:

Be it known that I, GEORGE C. WILDER, of Lawrence, in the county of Douglas, and State of Kansas, have invented new and Improved Punches; and I do hereby declare that the following is a full, clear, and exact description thereof, which will enable others skilled in the art to make and use the same, reference being had to the accompanying drawings, forming part of this specification.

This invention relates to a new and improved method of constructing punches, for the punching of nuts and washers, whereby the washers or nuts are more rapidly and economically made.

It consists of a follower, forced upwards against the washer or nut, after the same has been formed, by the force of a spring, whereby the washer or nut is freed from the punch.

It consists also of a central stationary punch, over which the movable outer punch works, whereby a centre hole is punched in the nut or washer, at the same time that the washer or nut is punched out of the bar.

In the accompanying plate of drawings—

Figure 1 represents a central vertical section of my invention, taken in the line $x-x$, fig. 2.

Figure 2 is a side view of the same.

Similar letters of reference indicate corresponding parts.

A is the frame.

B is the outer or movable punch.

C is the central or fixed punch.

D is the follower.

E is the spring.

G is the support for the punch C.

a is a hole in the punch B, to receive and carry off the metal punched out by the punch C.

H is the die.

The frame A is made of iron, or other suitable material, supported by suitable legs, in the form as shown in the drawing, or in any other suitable form, so as to be of sufficient strength for the punching of nuts or washers upon the same, and is provided, through the neck of the same, with a movable punch, B, held up by the force of a spring, or otherwise, in the ordinary way, and has, under the same, let into the frame A, a steel-tempered die, H, also in the ordinary way.

The die H is provided with a shoulder, to prevent the same from being forced through the frame A, and is provided in the centre with a hole, exactly under the punch B, said hole being of the same shape, and nearly the same size, as the face of the punch B.

Under the frame A, at any convenient distance therefrom, and supported by suitable attachments to the frame A, is a supplementary frame or support, G, as shown in the drawing.

Upon the support G, and rigidly secured thereto in

a vertical position, is a fixed or stationary punch, C, said punch C being so finished at the upper end or face of the same as to punch a round hole in the washer or nut, and correspond exactly with a hole, a , in the punch B, and extend upwards so as to be at the face of the same at the same height as the top of the die H.

The hole a , in the punch B, extends upwards and outwards, so as to form a passage for the metal punched from the nut or washer by the punch C.

Within the hole in the die H, and so as to move freely within the same, and so also as to move freely upon the punch C, a hole being bored through the centre of the same to receive the punch C, is a follower, D. The follower D is made of steel, properly tempered, and is provided upon the under side with a shoulder, to prevent the top or face of said follower D from being forced upwards above the height of the top of the die H.

Upon the frame G is a bent spring, E, resting by the ends of the same upon the frame G, and extending upwards so as to support the follower D, and so as, when the follower D is forced down by the punch B, the follower D will be forced upwards to the place of same by the force of the spring E, a hole being made in the centre of the spring E to receive the punch C through the same, and so that said spring may move up and down, partly over the punch C.

The punches B and C are made of steel, properly tempered in the ordinary way, and may be any form, so as to make the washers or nuts, or the hole in the same, of any required form.

The operation is similar to that of other punches in common use, and is readily seen from the drawing and the above description, the follower D freeing the washer or nut from the punch C. The same may be easily pushed from the frame A by the iron bar in the hand of the operator.

Constructed as above described, it constitutes a convenient punch for punching nuts or washers from metallic bars or plates, whereby the same are more rapidly and economically punched.

The combination of punches B and C, die H, and follower D, I do not claim, for it is substantially the same as that described in the withdrawn application of Lormer & Siess, in 1854; but

What I do claim, and desire to secure by Letters Patent, is—

Combining, with said combination, the spring E, as and for the purpose described.

GEORGE C. WILDER.
